OVEN VENT CONSTRUCTION

Elmer D. Pellegrin, Woodstock, and John F. Hennessy, Rockford, Ill., assignors to Geo. D. Roper Corporation, Rockford, Ill., a corporation of Illinois

Application October 24, 1941, Serial No. 416,300

12 Claims. (Cl. 126—21)

This invention relates to an improved oven vent construction for domestic gas ranges.

Oven vents have heretofore usually been constructed to deflect the products forwardly and downwardly over the cooking top, but in many cases such abrupt change in the direction of flow resulted in objectionable slowing down in the discharge of the products. A salient feature of the vent structure of our invention lies in the fact that the products are deflected forwardly from the back rail only enough to avoid contact with the wall behind the range but not enough to be noticeable to the housewife standing in front of the range or enough to slow up the escape of the products from the oven or ovens.

One of the objects of the invention is to provide an oven vent structure in which the grill fairly effectively obscures the discharge end of the flue, while nevertheless allowing substantially unobstructed discharge of products from the flue.

Another object consists in specially constructing the flue and providing inwardly projecting flanges defining the vent opening in the back rail so that the flue fits into the opening well enough to insure free and unobstructed escape of the products.

Another important object of the invention consists in the provision of an oven vent structure of the kind mentioned, the outer grill of which is applicable to the top of the back rail interchangeably in either one of two positions, so that it is adaptable to use on different styles of ranges having back rails of different dimensions, the fastening studs on the grill being disposed in a plane bisecting the front top corner portion of the grill so as to be insertible in spring clip fasteners provided therefor in the front top corner of the back rail in either of the two positions of the grill reversed end for end relative to the back rail.

Still another object consists in the provision of a grill for an oven vent structure of the kind mentioned having easily fracturable knock-out portions thereon, which are removed only when the grill is placed on a range equipped with electric light fixtures where the standards for the fixtures require notches formed by the removal of the knock-out portions, these portions being otherwise substantially indistinguishable from the outside of the grill.

The invention is illustrated in the accompanying drawings, in which:

Figure 1 is a perspective view of the top portion of a gas range equipped with an oven vent made in accordance with our invention;

Fig. 2 is a front view of a portion of the back rail showing the vent;

Fig. 3 is a top view of a portion of Fig. 2;

Fig. 4 is a vertical section on the line 4—4 of Fig. 2 looking in the direction of the arrows;

Fig. 5 is a perspective view similar to Fig. 1 but showing another range having two oven vents in the back rail and having electric light fixtures mounted on the back rail at the vent locations;

Fig. 6 is a front view of a portion of one of the grills shown in Fig. 5;

Fig. 7 is a top view of Fig. 6;

Fig. 8 is an enlarged sectional detail on the line 8—8 of Fig. 2, and

Fig. 9 is a vertical section approximately on the line 9—9 of Fig. 5.

Similar reference numerals are applied to corresponding parts throughout the views.

Referring first to Figs. 1 to 4, the reference numeral 10 designates the oven vent structure generally, the grill 11 of which is applied to the back rail 12 on the cooking top 13 of a domestic gas range 14. The back rail 12 is formed from sheet metal to provide a vertical front wall 14, a horizontal top wall 15, and a downwardly projecting rear wall or flange 16. An elongated substantially rectangular vent opening 17 is provided in the back rail, partly in the front wall 14 and partly in the top wall 15, as clearly appears in Fig. 4, and is defined by an inwardly directed flange 18, the upper and lower lengths of which are made to extend substantially parallel to one another at an angle of approximately forty-five degrees to the top and front walls, 15 and 14 respectively, as indicated at 19 and 20, that being the approximate direction of flow of the products through the vent opening 17, as indicated by the arrow 21 in Fig. 4. 22 is the substantially vertical upper discharge end portion of the flue extending upwardly from the oven compartment or compartments of the range, as, for example, is illustrated in Patent No. 2,336,988 to James F. Hennessy. In the present oven vent structure the upper end portion of the flue 22, which is generally rectangular in cross-section and of approximately the same width as the vent opening 17, is disposed with the front wall 23 thereof behind and in contact with the edge of the flange 20 and with the rear wall 24 thereof in front of and contacting the flange 16, whereby to locate the upper end portion of the flue in the proper fore and aft spaced relation to the front wall 14 of the back rail 12 and in approximate register with the vent opening 17. The front wall 23 of the flue has its upper end portion cut away,

as indicated at 25, in order to have the lower portion of the vent opening 17 in communication with the flue for unobstructed discharge of products of combustion from the oven or ovens. A sheet metal baffle plate 26 extends forwardly and upwardly from the back wall 24 in the upper end of the flue 22 at an angle of approximately forty-five degrees to said wall for contact with the lower side of the flange 19, whereby to deflect products of combustion forwardly and upwardly with respect to the back rail 12. This baffle plate has a lower edge portion 27 welded, as indicated, to the back wall 24. The plate 26 extends nearly the full width of the flue 22, being just wide enough to fit easily in the upper end of the vent opening 17 between the side flanges 18 thereof. In that way the baffle plate accurately locates the flue with respect to the vent opening. It should be clear, therefore, that with the flue 22 in such interfitting relationship to the back rail 12, the vent opening is in full communication with the flue, and inasmuch as the vent opening is substantially larger in cross-section than the flue there is nothing to interfere with free discharge of products of combustion.

The grill 11 is substantially L-shaped so as to rest with one leg of the L on top of the back rail, with the other leg engaging the front of said rail. The grill is herein shown as a one-piece aluminum die casting, although the same may be stamped from a single piece of sheet metal. The grill comprises a generally rectangular frame 28 having a series of parallel bars 29 extending across the smaller dimension thereof and joined at their ends to the longitudinal portions 30 and 31 of the frame 28. That leg of the L of which the longitudinal portion 31 forms a part is appreciably longer than the other leg of the L, the portion 31 being proportionately wider than the portion 30, as best shown in Fig. 4. This difference in length of the two legs of the L defined by the grill 11 is to adapt the grill to use interchangeably on two different styles of back rails, the grill being placed with the short leg portion 30 on top when applied to a shallow back rail, like that shown at 12 in Fig. 4, but being reversed end for end so as to have the long leg portion 31 on top when the grill is placed in a deeper style back rail, like that shown at 12a in Fig. 9. The grill has two studs 32 projecting downwardly and rearwardly therefrom in substantial parallelism to one another on the opposite ends of the frame 28. These studs are in a plane parallel to the flanges 19 and 20 and baffle plate 26 bisecting the angle of the L defined by the grill. In that way the studs can be entered in spring clip type fasteners mounted in the front upper corners of the back rails 12 and 12a in either of the two positions previously mentioned. That is to say, the end for end reversal of the grill will make no difference in so far as entry of the studs in the fasteners is concerned, and both legs of the L will seat neatly on the back rail when the studs are pushed all the way in. The interchangeability of the grills for use on different styles of ranges results in a substantial saving in cost and makes it a simple matter to replace broken or damaged grills.

The grills 11, as previously stated, are preferably aluminum die castings. That makes them impervious to the products discharged therethrough from the flues, and it also has the advantage that when the entire outer surface 34 of the grill is buffed off, the shiny surfaces on the bars 29 and frame 28 greatly enhance the appear-

ance of the grill. The grill may be dipped or sprayed with black enamel before this buffing, so as to blacken the opposite sides of all of the bars 29, as indicated by the stippling at 35 in Fig. 4, and also to blacken the recessed portions 36 in the frame 28 between the ends of the bars, as indicated by the stippling in Figs. 2 and 3. This blackening of all portions of the grill except the front shiny surfaces has an effect on the eye tending to distract attention from the interior of the vent structure to the exterior, thus making the internal parts, such as the flue 22 and baffle 26, not at all easily discernible from in front of the range. That effect is easily enhanced by enameling the flange 18 with black enamel and also coating the inside of the upper end portion of the flue 22 and the front of the baffle 26 with black enamel, as indicated by the heavy shading of these portions in Fig. 4. There is, therefore, nothing noticeable from in front of the range, even close up, that might detract from the good appearance of the range.

In the range illustrated in Figs. 5 and 9, the back rail 12a it will be noticed has an upper section 37 joined to the lower section 38 by U-shaped sheet metal brackets, one of which is shown at 39 in Fig. 9, these being disposed in longitudinally spaced relation with respect to the sections 37 and 38. The ornamental separator strip 40 spaces the sections and is secured to the brackets 39 by T-bolts 41, the brackets, in turn, being fastened by screws 42 to the flanges 43 on the sections 37 and 38. The section 38 has another ornamental strip 40 spacing it from the upwardly projecting rear portion of the cooking top 13a, and the section 38 is joined to the cooking top 13a by another set of U-shaped sheet metal brackets 39 in the same way that the sections 37 and 38 are joined together. Back rail section 37 has a vent opening 17a provided therein, similar to the opening 17 in the back rail 12 and defined similarly by an inwardly directed marginal flange 18a. The flange defining the rectangular opening 17a serves to locate the discharge end portion 44 of the flue 22a, which, like the flue 22, serves to conduct products of combustion from the oven compartment upwardly to the vent opening. There are two of these flues in the range illustrated in Fig. 5, one for each of the oven vent structures indicated generally by the reference numerals 10a, the left hand flue being associated with the left hand oven in the range 14a and the right hand flue with the right hand oven. The upper discharge end portion 44 of each of the flues extends forwardly at an angle of approximately forty-five degrees to the vertical front and back walls of the flues to enter the vent openings in the manner illustrated in Fig. 9. In that way good registration is insured between the flues and their associated vent openings to insure free and unobstructed discharge of products from the ovens. The forwardly inclined upper end portions 44 of the flues when entered in the vent openings are brought into engagement with the upper lengths 19a of the flanges 18a, and in sliding upwardly on these flanges the upper end portions of the flues 22a are located in closely spaced relation to the lower lengths 20a of the flanges 18a, substantially as shown in Fig. 9. The flues are, of course, suitably secured to the back of the range when their upper ends are located in the manner stated. The exposed side of the flanges 18a and the exposed inner sides of the upper end portions of the flues are coated with black enamel, similarly as in the

other range previously described and as indicated by the heavy shading in Fig. 9, for a similar purpose.

The electric light fixtures indicated at 45 have supporting standards 46 entered through holes 47 provided in the top wall 15a of the back rail, and are fastened by means of screws 48 entered through holes in the rear flange 16a on the back rail and threaded in holes provided therefor in the standards. The grills 11 have to be notched out, as indicated at 49, to fit around these standards. We have, therefore, provided knock-out portions 49a in the edge of the grill, as indicated in Fig. 2 and as illustrated in the enlarged section in Fig. 8. These knock-out portions have thin walls 50 along the U-shaped outline for the notch so that a workman can easily break these portions out with a pair of pliers, without danger of damaging the grill otherwise. The notches 49 thus defined are only slightly jagged, but straight enough to serve the purpose intended. On the other hand, there is nothing on the outside of these grills to indicate where these knock-out portions are, the recesses indicated at 50 in Fig. 8 being entirely from the inner side in the form of a U to outline the knock-out portions for the notches. In that way the same style of grill can be used not only on two different styles of ranges but also on ranges with or without light fixtures.

It is believed the foregoing description conveys a good understanding of the objects and advantages of our invention. The appended claims have been drawn with a view to covering all legitimate modifications and adaptations.

We claim:

1. The combination with a gas stove having a back rail projecting upwardly from the cooking top, the back rail having a rearwardly projecting top portion, of an oven outlet flue extending upwardly behind the back rail, the back rail having a vent opening in the upper portion thereof enlarged so as to extend rearwardly a substantial distance into the rearwardly projecting top portion, said opening being in vertical alignment with the upper end of the outlet flue, and deflector means for directing flue products from the flue at an acute angle relative to the vertical and upwardly and forwardly through said vent opening.

2. The combination with a gas stove having a back rail projecting upwardly from the cooking top, the back rail having a rearwardly projecting top portion, of an oven outlet flue extending upwardly behind the back rail, the back rail having a vent opening in the upper portion thereof enlarged so as to extend rearwardly a substantial distance into the rearwardly projecting top portion, said opening being in vertical alignment with the upper end of the outlet flue, deflector means for directing flue products from the flue at an acute angle relative to the vertical and upwardly and forwardly through said vent opening, and an L-shaped flue grill mounted on said back rail over the vent opening providing portions abutting the upwardly and rearwardly extending portions of the back rail adjacent the opening.

3. The combination with a gas stove having a back rail projecting upwardly from the cooking top, the back rail having a rearwardly projecting top portion terminating in a downwardly projecting rear flange, of an oven outlet flue extending upwardly behind the back rail with the back of the flue in abutment with the front

of the rear flange, the back rail having a vent opening in the upper portion thereof enlarged so as to extend rearwardly a substantial distance into the rearwardly projecting top portion, said opening being defined by an inwardly projecting marginal flange having abutment with the front of the outlet flue to locate the latter in rearwardly spaced relation to the back rail, said outlet flue having the upper portion of the front wall thereof cut away to establish communication with the vent opening.

4. The combination with a gas stove having a back rail projecting upwardly from the cooking top, the back rail having a rearwardly projecting top portion terminating in a downwardly projecting rear flange, of an oven outlet flue extending upwardly behind the back rail with the back of the flue in abutment with the front of the rear flange, the back rail having a vent opening in the upper portion thereof enlarged so as to extend rearwardly a substantial distance into the rearwardly projecting top portion, said opening being defined by an inwardly projecting marginal flange having abutment with the front of the outlet flue to locate the latter in rearwardly spaced relation to the back rail, said outlet flue having the upper portion of the front wall thereof cut away to establish communication with the vent opening, and a baffle in the upper rear portion of the outlet flue for deflecting flue products at an acute angle relative to the vertical and forwardly and upwardly through said vent opening.

5. The combination with a gas stove having a back rail projecting upwardly from the cooking top, the back rail having a rearwardly projecting top portion terminating in a downwardly projecting rear flange, of an oven outlet flue extending upwardly behind the back rail with the back of the flue in abutment with the front of the rear flange, the back rail having a vent opening in the upper portion thereof enlarged so as to extend rearwardly a substantial distance into the rearwardly projecting top portion, said opening being defined by an inwardly projecting marginal flange having abutment with the front of the outlet flue to locate the latter in rearwardly spaced relation to the back rail, said outlet flue having the upper portion of the front wall thereof cut away to establish communication with the vent opening, and a baffle in the upper rear portion of the outlet flue for deflecting flue products forwardly and upwardly through said vent opening, the upper end portion of said baffle projecting into the rear portion of the vent opening so as to locate the outlet flue against lateral displacement with respect to the vent opening.

6. The combination with a gas stove having a back rail projecting upwardly from the cooking top, the back rail having a rearwardly projecting top portion terminating in a downwardly projecting rear flange, of an oven outlet flue extending upwardly behind the back rail with the back of the flue in abutment with the front of the rear flange, the back rail having a vent opening in the upper portion thereof enlarged so as to extend rearwardly a substantial distance into the rearwardly projecting top portion, said opening being defined by an inwardly projecting marginal flange having abutment with the front of the outlet flue to locate the latter in rearwardly spaced relation to the back rail, said outlet flue having the upper portion of the front wall thereof cut away to establish communication with the vent opening, and an L-shaped

flue grill mounted on said back rail over the vent opening providing portions abutting the upwardly and rearwardly extending portions of the back rail adjacent the opening.

7. The combination with a gas stove having a back rail projecting upwardly from the cooking top, the back rail having a rearwardly projecting top portion terminating in a downwardly projecting rear flange, of an oven outlet flue extending upwardly behind the back rail with the back of the flue in abutment with the front of the rear flange, the back rail having a vent opening in the upper portion thereof enlarged so as to extend rearwardly a substantial distance into the rearwardly projecting top portion, said opening being defined by an inwardly projecting marginal flange having abutment with the front of the outlet flue to locate the latter in rearwardly spaced relation to the back rail, said outlet flue having the upper portion of the front wall thereof cut away to establish communication with the vent opening, a baffle in the upper rear portion of the outlet flue for deflecting flue products at an acute angle relative to the vertical and forwardly and upwardly through said vent opening, and an L-shaped flue grill mounted on said back rail over the vent opening providing portions abutting the upwardly and rearwardly extending portions of the back rail adjacent the opening.

8. The combination with a gas stove having a back rail projecting upwardly from the cooking top, the back rail having a rearwardly projecting top portion, of an oven outlet flue extending upwardly behind the back rail, the back rail having a vent opening in the upper portion thereof enlarged so as to extend rearwardly a substantial distance into the rearwardly projecting top portion, said flue having an upper discharge end portion extending at an acute angle relative to the vertical and forwardly and upwardly into the vent opening so as to direct flue products at an acute angle relative to the vertical and upwardly and forwardly through said opening while holding the flue against lateral displacement with respect to said opening, and an L-shaped flue grill mounted on said back rail over the vent opening providing portions abutting the upwardly and rearwardly extending portions of the back rail adjacent the opening.

9. The combination with a gas stove having a back rail projecting upwardly from the cooking top, the back rail having a rearwardly projecting top portion, of an oven outlet flue extending upwardly behind the back rail, the back rail having a vent opening in the upper portion thereof enlarged so as to extend rearwardly a substantial distance into the rearwardly projecting top portion, the vent opening being defined by an inwardly projecting marginal flange, said flue having an upper discharge end portion extending at an acute angle relative to the vertical and forwardly and upwardly into surface to surface engagement with the flange so as to locate the flue with respect to the vent opening and direct flue products at an acute angle relative to the vertical and forwardly and upwardly through said opening, and an L-shaped flue grill mounted on

said back rail over the vent opening providing portions abutting the upwardly and rearwardly extending portions of the back rail adjacent the opening.

10. The combination with a gas stove having a back rail projecting upwardly from the cooking top, the back rail having a rearwardly projecting top portion, of an oven outlet flue extending upwardly behind the back rail, the back rail having a vent opening in the upper portion thereof enlarged so as to extend rearwardly a substantial distance into the rearwardly projecting top portion, said opening being in communication with the upper end of the outlet flue and serving to discharge therethrough products from said flue upwardly and forwardly with respect to the back rail.

11. The combination with a gas stove having a back rail projecting upwardly from the cooking top, the back rail having a rearwardly projecting top portion, of an oven outlet flue extending upwardly behind the back rail, the back rail having a vent opening in the upper portion thereof enlarged so as to extend rearwardly a substantial distance into the rearwardly projecting top portion, said opening being in communication with the upper end of the outlet flue, a flue grill of inverted L-shape adapted to rest with one leg thereof in abutment with the front of the back rail and the other leg resting on the top portion, the middle portion of said grill covering the vent opening, and means for detachably securing said grill to said back rail comprising studs on the opposite ends of said grill projecting inwardly therefrom in parallel relation to one another and in a plane bisecting the angle formed by the two legs of the L, and fasteners for receiving said studs mounted on the back rail on opposite sides of the vent opening in coaxial relationship to said studs.

12. The combination with a gas stove having a back rail projecting upwardly from the cooking top, the back rail having a rearwardly projecting top portion, of an oven outlet flue extending upwardly behind the back rail, the back rail having a vent opening in the upper portion thereof enlarged so as to extend rearwardly a substantial distance into the rearwardly projecting top portion, said opening being in communication with the upper end of the outlet flue, a flue grill of inverted L-shape adapted to rest with one leg thereof in abutment with the front of the back rail and the other leg resting on the top portion, the middle portion of said grill covering the vent opening, and means for detachably securing said grill to said back rail comprising studs on the opposite ends of said grill projecting inwardly therefrom in parallel relation to one another and in a plane bisecting the angle formed by the two legs of the L, and fasteners for receiving said studs mounted on the back rail on opposite sides of the vent opening in coaxial relationship to said studs, said grill being reversible end for end and applicable by means of said studs in the same fasteners in the reversed position.
